CALENDAR HAVING FOLDING, ADJUSTABLE
DATE ELEMENTS SLIDABLY RECEIVABLE
IN SUPPORTING FRAME

Harvey Lathrop, Forest Hills, N. Y.

Application April 10, 1945, Serial No. 587,515

4 Claims. (Cl. 40—119)

1

My present invention relates generally to calendars, and has particular reference to the type of calendar device which is adjustable in such a way that its utility is not limited to any particular period of time.

In a "perpetual" calendar of the kind to which my invention is primarily applicable, a means is provided for displaying a month designation in association with a series of well-known calendar-type columns in which integers are arranged in weekly sections, i. e., each column having a series of numbers increasing by increments of seven. Coupled with these columnar markings is a relatively fixed heading which designates the seven days of the week. By adjusting the columnar markings so as to bring the number "1" under or in alignment with a selected day of the week, any desired arrangement of days may be depicted.

This general idea is well-known per se, and the objectives of my present invention are directed solely to an improved construction and arrangement of parts whereby a number of new advantages are achieved.

It is a general object of the invention to provide a device which is unusually compact, composed of relatively few and simple structural elements, easy to adjust in the contemplated fashion, and highly attractive in appearance. More particularly, my invention aims to provide a device which is substantially flat, hence useful in a variety of practical embodiments; and whose manufacture lends itself readily to the employment of numerous different materials of ornamental character.

As in many of the devices heretofore known, the present structure comprises, in essence, at least one element which may be defined as a date-indicating element, and a supporting frame with which the element is adjustably associated. A feature of the present invention resides in the provision of this date-indicating element in the form of hingedly-interconnected sections arranged in side-by-side relationship, each section being relatively rigid, and each hinge being of such character that any selected section may be folded back flatwise against its adjacent section. In this way, a doubling under of certain selected sections results in the formation of an adjusted flat unit of reduced length displaying on its exposed face only a selected group of sections. Moreover, the hinges are so constructed that each section may be folded back either forwardly or rearwardly, thereby rendering both faces useful to bear date markings of the character desired, and permitting a relatively large number of dis-

2

play variations to be achieved in a relatively small space.

The frame of the present device has a recess adapted snugly to accommodate the flat unit referred to, and the recess length is preferably equal to at least one-half the over-all length of the sectional element, whereby the latter is at all times, and in all adjusted conditions thereof, of predetermined two-ply thickness, the recess having a corresponding depth.

The preferred structure includes two date-indicating elements, one for the month designations, the other for the columnar designations. Where one or more such elements are employed, at least one of said elements is composed of separate strips of rigid flat stock, and the hinges are composed of relatively thin flexible sheet material, interconnecting said strips. Preferably, the sectional element comprises a belt of flexible sheet material with the rigid strips secured thereto in slightly spaced side-by-side relationship. In one embodiment, there is one set of strips secured to one surface of the belt, and a second registering set secured to the opposite surface thereof. In an alternative embodiment, the belt is composed of two plies secured together along the hinge lines and forming pockets between the hinge lines to accommodate said strips. In the former case, the rigid strips are exposed, and may be composed of ornamental glass, plastic, wood, metal, or the like. In the latter case, the belt material is exposed, and may be composed of ornamental fabric, leather, flexible plastic, or equivalent sheet material.

Of particular merit is the fact that the present device as a whole is neatly flat in nature and appearance, and is devoid of rollers, adjustment knobs, and other extraneous elements of fundamentally unattractive character.

I achieve the foregoing objects and advantages, and such other objects and advantages as may hereinafter appear or be pointed out, in the manner illustratively exemplified in the accompanying drawings, in which:

Figure 1 is a perspective view of a calendar device constructed in accordance with the present invention;

Figure 2 is a fragmentary perspective view similar to Figure 1, with a portion of the frame removed to reveal the element beneath;

Figure 3 is an enlarged cross-sectional view taken substantially along the line 3—3 of Figure 1;

Figure 4 is a cross-sectional view taken substantially along the line 4—4 of Figure 1;

Figure 5 is an obverse view of the month-designating sectional element;

Figure 6 is a reverse view of the same;

Figure 7 is an edge view of the same;

Figure 8 is a perspective view of said element shown in an adjusted position different from that of Figures 1-3;

Figure 9 is an obverse view of the main sectional element;

Figure 10 is a reverse view thereof; and

Figure 11 is a cross-sectional view through a modified type of sectional element.

In the embodiment herein chosen for illustration, a substantially rectangular frame 20 is adapted to accommodate the two adjustable sectional elements 21 and 22, the former being shown by itself in Figures 9 and 10, the latter being shown by itself in Figures 5-8.

The frame 20 may be composed of any suitable rigid material, such as plastic, wood, metal, or the like, and it may assume a variety of different structural forms. Merely for illustrative purposes, I have shown the frame composed of a back wall 23, and thickened forwardly-extending margins 24, 25 and 26, the margin 25 being arranged along the bottom edge of the frame, and the margins 24 and 26 being arranged along the sides. These margins are provided with an inwardly-facing groove 27 which defines a recess of predetermined depth within which the sectional elements 21 and 22 are accommodated. Access to the recess is afforded through the upper edge portion of the frame, and after the parts are in the relationship shown in Figure 2, a separable frame portion 28 is inserted downwardly through the upper portion of the device. The frame portion 28 has lateral projections 29 which fit into the grooves 27, and a face portion provided with a recess 30. The frame portion 28 is also provided with the fixed designations 31, representing the seven days of the week.

The sectional element 22 is composed of a web or belt 32 (see particularly Figure 7) which may be of any suitable relatively thin flexible material such as fabric or the like. Secured to one face of this belt are a series of relatively rigid strips 33-38 arranged in slightly spaced side-by-side relationship. Secured to the opposite face of the belt 32 are a corresponding series of rigid strips 39-44, the strip pairs being respectively in registry so that the resultant element is composed of hingedly-connected rigid sections. The portions of the belt 32 which lie between the rigid sections of the element are hinges, and are of such a character that each section may be freely folded back to lie flatwise against the adjacent section. Moreover, this adjustment is possible either forwardly or rearwardly, so that both surfaces of the sectional element may be employed for the reception of suitable date markings. The markings on the element 22 are the twelve months of the year, as shown most clearly in Figures 5 and 6.

As illustrations of the varied adjustability of this element, attention is directed to a comparison of Figures 2 and 8. In Figure 2, the section bearing the strip 33 has been folded back rearwardly along the hinge line 45, and the section bearing the strip 37 has been folded back along the hinge line 46, thus forming a two-ply flat unit in which the strips 34, 35 and 36 are exposed forwardly.

In Figure 8, on the other hand, the parts have been adjusted along different hinge lines so that the strips 38, 33 and 34 are exposed forwardly.

By similar adjustments, any desired strip may

be centrally positioned in the resultant flat unit, and may thus be caused to show through the aperture 30. Obviously, if the aperture 30 is laterally positioned, rather than in the central disposition shown, a correspondingly - different month designation will show through. In any case, any desired month may be caused to show through the aperture 30, and in each adjusted condition of the sectional element, the six sections are arranged in the compact relationship shown. This compacted unit, it will be observed, is of reduced length with respect to the over-all length of the sectional element (Figures 5-7), and the recess in the frame is of such a length that it will snugly accommodate this unit.

The other sectional element 21, shown most clearly in Figures 3, 9 and 10, is similarly constructed, except that the rigid strips are elongated in a vertical direction, and bear number designations in well-known columnar fashion. More particularly, a belt 41 of relatively thin flexible sheet material is secured to a series of rigid strips 48-60 mounted on its front face in slightly spaced side-by-side relationship, and carries on its rear face a second set of registering rigid strips 61-73. This results, as before, in forming a series of adjacent rigid sections interconnected by hinges which permit any selected section to be folded down, either forwardly or rearwardly, into flatwise relationship to the adjacent section.

In adjusting the element 21 to fit the frame 20, a selected group of seven adjacent sections is caused to face forwardly, and the proper selection depends upon the month which is sought to be depicted. For example, if the month has thirty-one days and the first of the month falls on a Sunday, the sections 54-60 are exposed forwardly, the other six sections being folded rearwardly along the hinge line 74 (Figure 9) to lie in a rearward layer. Or, if the month has thirty days, and the first of the month falls on a Monday, the sections 66-72 will be caused to face forwardly, the other sections being folded rearwardly along the hinge lines 75 and 76 respectively (see Figure 10.) In the particular month depicted in Figures 1-3, it is the sections 50-56 which are directed forwardly, the remaining sections lying in the rear as shown most clearly in Figure 3.

Here, too, it will be observed, the resultant flat unit is of reduced length with respect to the over-all length of the sectional element (Figures 9-10), and the recess in the frame has a length adapted to accommodate this unit.

In the illustrated device, the adjustment of the parts is accomplished by removing the frame portion 28, removing the sections 21 and 22, adjusting the section 21 into the desired two-ply relationship and reinserting it endwise into the frame, adjusting the section 22 into the desired two-ply relationship and inserting it into the frame, and then finally replacing the frame portion 28. This having been accomplished, the device presents to view a flat and compact calendar for the selected month, and may be supported on any suitable base or prop, or may lie flat on a table or other support. Because of its neatly flat nature, it may be readily associated with other accessories, as a desk pad, or the like. By virtue of the present structural design, the various rigid panels may be composed of highly polished plastic, metal, or other ornamental material, thus not necessarily requiring any protective cover.

Needless to say, the frame may be constructed

in a variety of ways other than that shown herein.

As an alternative way of constructing one or both of the adjustable sectional strips, I have shown in Figure 11 the possibility of employing a belt composed of the two plies 77 and 78. These two plies are of relatively thin flexible sheet material, are secured together along the hinge lines 79, 80, 81, etc., and form pockets between the hinge lines within which rigid strips 82 may be accommodated. In this case, the rigid strips 82 are not exposed to view, and may be composed of less expensive, non-ornamental material, while the belt material will be chosen for its ornamental value. This material may be, for example, ornamental leather, flexible plastic, a suitable fabric, or the like.

The securing of the strips to the belt material, both in the form shown in Figure 7 and that shown in Figure 11, may be achieved by adhesive means or otherwise, as may be desired. Along the hinge lines of Figure 11, the two plies of the belt may be secured together by adhesive means, by stitching, or otherwise.

It will thus be observed that I have provided a so-called "perpetual" calendar device which is devoid of unattractive bulkiness, which is unusually compact and attractive, and which lends itself admirably to the employment of various ornamental materials which contribute to an over-all appearance which is pleasing and ofesthetic value.

Having thus described my invention and illustrated its use, what I claim as new and desire to secure by Letters Patent is:

1. In an adjustable calendar device, a month-indicating element comprising a series of hingedly-connected rigid sections bearing different month markings thereon, the hinges being of such character that any section may be folded back to lie flatwise against its adjacent section, whereby the doubling-under of selected sections will form an adjusted flat unit of reduced length displaying on its exposed face only a selected group of month markings, a supporting frame comprising a rear wall and grooved side walls, said flat unit being removably insertable endwise into said grooves, for snug accommodation in the region between them, and a removable shield adapted to overlie said accommodated unit and provided with an aperture revealing only one of said month markings.

2. In an adjustable calendar device, a month-indicating element comprising a series of hingedly-connected rigid sections bearing different month markings thereon, the hinges being of such character that any section may be folded back to lie flatwise against its adjacent section, whereby the doubling-under of selected sections will form an adjusted flat unit of reduced length displaying on its exposed face only a selected group of month markings, a supporting frame comprising a rear wall and grooved side walls, said flat unit being removably insertable endwise into said grooves, for snug accommodation in the region between them, and a removable shield adapted to overlie said accommodated unit and provided with an aperture revealing only one of said month markings, said hinges allowing each section to be folded back either rearwardly or forwardly, whereby both surfaces of said sectional element may be used for said month mark-

ings, said element comprising six sections and said recess having a depth equal to at least twice the thickness of each section and having a length equal to half the over-all length of said sectional element.

3. In an adjustable calendar device, a date-indicating element comprising a series of hingedly-connected vertically elongated rigid sections arranged in side-by-side adjacence and bearing calendar-type successive columns of integers, each section bearing on its face only a single column of said integers, the hinges being of such character that any section may be folded back to lie flatwise against its adjacent section whereby selected sections may be doubled under to form a flat unit displaying on its exposed face a selected group of at least seven adjacent columns, and a supporting frame comprising a rear wall and grooved side walls, said flat unit being removably insertable endwise into said grooves for snug accommodation in the region between them with seven of said columns forwardly exposed to view.

4. In an adjustable calendar device, a pair of date-indicating elements each of which comprises a series of hingedly-connected rigid sections, the sections of one of said elements bearing different month markings thereon, the sections of the other of said elements bearing calendar-type columns of integers, there being one column on each section, the hinges of each of said elements being of such character that any section may be folded back to lie flatwise against its adjacent section, whereby the doubling-under of selected sections of each element will form two adjusted flat units of reduced length, one unit displaying on its exposed face only a selected group of month markings, the other unit displaying on its exposed face only a selected group of seven adjacent columnar markings, a common supporting frame having opposed grooves adapted to snugly accommodate said adjusted flat units in side-by-side relation, and a removable shield adapted to overlie the accommodated unit bearing month markings and provided with an aperture revealing only one of said month markings, said shield bearing a row of symbols designating the seven days of the week and arranged in alignment, respectively, with said seven exposed columnar markings.

HARVEY LATHROP.
